UNITED STATES PATENT OFFICE.

HENRY LEITNER, OF WOKING, RICHARD NORMAN LUCAS, OF BYFLEET,
AND HARRY HILL, OF WOKING, ENGLAND; SAID HILL ASSIGNOR TO
SAID LEITNER AND LUCAS.

AUTOMATIC ELECTRIC SWITCH, PARTICULARLY FOR USE IN CHARGING ELECTRIC ACCUMULATORS.

No. 831,959.

Specification of Letters Patent.

Patented Sept. 25, 1906.

Application filed February 10, 1905. Serial No. 245,129.

To all whom it may concern:

Be it known that we, HENRY LEITNER, residing at Maybury, Woking, RICHARD NORMAN LUCAS, residing at Lynton, Dartnel Park, Byfleet, and HARRY HILL, residing at Woking, in the county of Surrey, England, subjects of the King of Great Britain, have invented new and useful Improvements in Automatic Electric Switches, Particularly for Use in Charging Electric Accumulators, of which the following is a specification.

Our invention refers to certain improvements in automatic switches of the type employed for automatically connecting and disconnecting dynamo-electric generators from batteries of accumulators which they are arranged to charge. Our present invention is designed to get rid of the "hunting" to which most of these automatic switches are liable and provides means of short-circuiting the resistance of positive temperature coefficient which forms a feature of our systems until the dynamo excites and of breaking the short-circuit after it has excited and when it as yet produces only a relatively small electromotive force and one insufficient to actuate an automatic switch of any of the types ordinarily in use.

In Patent No. 738,113 is shown one form or arrangement of devices illustrative of what has just been termed "our systems."

We carry out our invention in practice by arranging in the circuit an electromagnet adapted to attract an armature when it is energized. This armature makes a contact when it is in its off or unattracted position and a contact or contacts when attracted. The contact which the said electromagnet makes in its said off position is arranged to short-circuit the said positive-temperature-coefficient resistance. The other two contacts are arranged so that when one of them is made by the armature being attracted by the above-described electromagnet it puts the armature of the automatic cut-out across the terminals of the battery of accumulators, while the second contact puts the fine-wire field-winding of the cut-out in series with the dynamo, so that it tends to charge the battery of accumulators through it.

In order that the nature of our invention may be the more fully understood, we refer to the accompanying drawing, which illus-

trates it as applied to a system of electric lighting comprising a main generator controlled by a subsidiary dynamo and a battery of accumulators charged by the main generator and an automatic switch.

In the drawings, *a* is the electromagnet, the windings of which are connected to the main generator *d* through the conductors *l*² and *l*³, so that it becomes energized when the main generator excites.

b is the armature of the said electromagnet, mounted on a plate of insulating material *b'*, this plate making in the off position the contact *c*⁰ *c*. On the insulating-plate *b'* is mounted a second metallic plate *c'*, which is adapted to make two contacts *c*² and *c*³ when the electromagnet *a* is energized and attracts its armature *b*. The contact *c* is connected to the conductor *l*¹ by the flexible connection *w*, and the conducting-plate *c'* is similarly connected to the conductor *l*⁴ by the flexible connection *w'*.

d represents the armature of the main generator, and *g* its series differential field-winding, *f* being its fine-wire shunt field-winding.

e is the armature of the demagnetizing or controlling dynamo, designed to weaken the current through the winding *f* as the speed at which the armature *d* is driven increases.

j is the fine-wire shunt field-winding of the controlling-dynamo. *h* is its series field-winding, and *i* is the resistance of positive temperature coefficient, which is, as will be seen, short-circuited by the contact *c*⁰ *c* through the conductors *l*², *l*¹, and *l*⁵.

k is the armature-winding of an automatic switch or cut-out for establishing (or breaking) connection between the generator *d* and the battery *B*, according as the electromotive force of the former exceeds or falls short of that of the latter.

m is the fine-wire field-winding in the same, and *n* the coarse-wire field-winding through which the charging-current passes from the main generator to the battery of accumulators *B* when they are being charged, *L* *L* being the incandescent lamps lighted by the latter.

p and *p'* are contact-pins carried upon the arm or lever of the automatic switch, designed to make contact in the mercury-trough *r* when the said switch operates and enable current to flow to the demagnetizer field-

winding j through the carbon resistances o and from the main generator to the battery B through the winding n .

The operation of the arrangement is as follows: In the position shown in the drawing, which illustrates the state of affairs when the main generator is at rest or until it has excited, the contact c short-circuits the resistance i , as already stated, by way of the conductors l^2 , l' , and l^3 , in this way facilitating the excitation of the main generator. When the main generator excites, the electromagnet a receives current through l^3 , l^6 , l' , and l^5 . It thereupon attracts its armature b , breaking the contact c , whereupon the plate c' establishes contact between c^2 and c^3 and the conductor l^4 , thereby putting c^2 and c^3 in direct connection with the positive terminal of the battery B. The armature k of the automatic switch or cut-out is thus placed across the terminals of the battery B, while the field-winding m of the automatic cut-out is put into series between the main generator and the positive terminal of the battery B. When the electromotive force of the generator continues to rise until it overpowers that of the battery B, the automatic switch is operated, owing to the increase of current passing through it, to cause the contacts p and p' to descend into the mercury-trough r , situated below them, the contact p' enabling the field-winding j of the demagnetizing-dynamo to obtain current through the carbon resistances o and the contact p , enabling the main generator to charge the battery B through the coarse-wire field-winding n of the automatic switch, the conductors l and l^4 and the mercury-trough r . It will be understood that the electromagnet a is so wound that it attracts its armature b and effects the various actions above described when the generator only produces a very small electromotive force. The armature k and the fine-wire field-winding m of the automatic switch therefore remain ener-

gized even when the charging-current flowing through n becomes very small, and in this way all possibility of the said automatic switch continuing to switch on and off when the dynamo is driven at some particular speed is averted.

Having now particularly described and ascertained the nature of our said invention and in what manner the same is to be performed, we declare that what we claim is—

1. The combination with an automatic switch for switching a generator or dynamo into and out of connection with a battery of accumulators which it is designed to charge, and having a movable electromagnetic armature and a field-magnet with fine and coarse wire windings, of an electromagnet and means for energizing the same from the generator when it develops a low electromotive force, and for then causing the electromagnet to make contacts which cause the armature of the automatic switch to be energized from the battery of accumulators and the fine-wire field-winding of the same to be put in series between the generator and the battery, substantially as described.

2. The combination with a generator, a battery of accumulators, an automatic switch having fine and coarse field-windings for switching the battery into and out of connection with the generator, of an electromagnet in circuit with said generator, a movable armature for said magnet for closing a circuit from said battery through the armature of said switch and also closing a circuit from both the said battery and said generator through the fine field-winding of said switch, substantially as described.
